UNITED STATES PATENT OFFICE

128,812

DESIGN FOR A PASTRY TRAY OR SIMILAR ARTICLE

Carl J. Uhrmann, Bellaire, Ohio, assignor to Imperial Glass Corporation, Bellaire, Ohio, a corporation of Ohio

Application May 24, 1941, Serial No. 101,127

Term of patent 14 years

To all whom it may concern:

Be it known that I, Carl J. Uhrmann, a citizen of the United States of America and resident of Bellaire, county of Belmont, and State of Ohio, have invented a new, original, and ornamental Design for a Pastry Tray or Similar Article, of which the following is a specification, reference being had to the accompanying drawing, forming part thereof, in which:

Figure 1 is a top plan view of a pastry tray or similar article, showing my new design; and

I claim:

The ornamental design for a pastry tray or similar article, substantially as shown.

CARL J. UHRMANN.
